STOP-MOTION FOR LOOMS.

1,150,493.

Specification of Letters Patent.

Patented Aug. 17, 1915.

Application filed January 9, 1915. Serial No. 1,447.

To all whom it may concern:

Be it known that we, TIMOTHY BOUCHARD, JOHN V. CUNNIFF, and PHILIP JONCAS, citizens of the United States, residing at Fall River, in the county of Bristol and State of Massachusetts, have invented a new and useful Improvement in Stop-Motions for Looms, of which the following is a specification.

This invention relates to certain new and useful improvements in stop motions for looms, and the primary object of the invention is to effect stoppage of the loom by and upon tightening of one or more of the warp threads.

A further object of the invention is to provide means of simple and economical structure for accomplishing the purpose set forth, which means is also positive and certain in its action.

A still further object of the invention is to provide means of the type indicated which can be attached to any ordinary loom easily and quickly and without alteration of the loom structure, and in addition to provide a stop motion which co-operates with the vibrator and the knock off of the loom to stop the loom and lock the stop motion.

In the drawings—Figure 1 is a fragmentary view of a loom shown in side elevation and partly in section. Figs. 2 and 3 are similar enlarged detail views showing the present invention in normal and stopping position. Fig. 4 is a detail perspective view showing the normal position of the rod which traverses the warp threads and normally maintains same depressed.

In carrying the invention into practice it is used in connection with a vibrator 1 that is commonly employed in connection with the stop motion of a loom for effecting stoppage of the loom upon thread breakage. A rod 3 extends transversely and entirely across the back of the loom, and normally holds the warp threads W in a slightly depressed position, as depicted in Fig. 2, and is carried by the vertically reciprocating arms 4, that are provided with rack teeth 5. The arms 4 are slidable in guides 12 formed upon standards 11, while the rod 3 is secured in the lower end of the arms 4 and has its ends preferably received in guide slots 10 formed in a pair of standards 11 which latter are appropriately secured to each side frame of the loom. A pawl 6 is appropri-

ately pivoted to each of the standards 11 and are held against downward movement by engagement with the arms 4. The upper ends of the standards 11 have levers 7 pivoted thereto intermediate the ends of the levers, the lever ends being pivoted to the drop wires or members 8 and the arms 4 so that the arms and drop wires will move in opposite directions when upward movement is given the arms 4 and the drop wires 8 which move in the guides or troughs formed by the two plates 2 and located either as in Fig. 1 or as in Figs. 2 and 3 will be lowered to come in contact with the vibrator 1.

Normally the parts occupy the position shown in Fig. 2. Should one or more of the warp threads be tightened, it will be apparent that rod 3 will be raised to the position shown in Fig. 3, thereby raising the arms 4 and lowering the drop wires 8 to a position where the drop wires extend across the path of the vibrator 1 as depicted in Fig. 3, which thus arrests the normal action of the vibrator and causes the action of the stop motion to knock off or stop the loom. The pawl 6 will upon raising of the arms 4 engage the rack teeth 5 and lock the arms in raised position.

When a warp thread breaks forward or backward of the harnesses and gets entangled with other unbroken threads, it prevents the dropping of drop wires which would operate the regular stop motion and the loom will weave what is commonly called over or under shot work which is defective cloth. When a thread breaks as above described the entanglement causes one or more of the warp threads to become tight which, acting on the rod 3, will cause the operation of the above described stop motion and cause the stopping of the loom.

Having thus described our invention, we claim as new and desire to secure by Letters Patent:

1. In a loom stop motion, in combination with the vibrator and drop member, standards secured at opposite sides of the loom and having slots therein, a rod engaged on top of the warp threads and having its ends projecting in said slots, vertical arms slidingly carried by the standards and connected to the rod and having rack teeth, pawls pivoted to the standards and engaged with the arms, and a lever pivoted intermediate its length to one of the standards and piv-

- oted at its ends to the drop member and to one of the arms.
2. In a stop motion for looms, in combination with the vibrator and drop member, means engaging on top of the warp threads for holding same depressed, means for supporting the first means, means for locking the supporting means against downward movement upon raising of the supporting means, and means between the supporting means and drop member for moving the drop member into the path of the vibrator when the first named means is raised by the tightening of the warp threads.
- 15 3. In a loom in combination with the drop member and a vibrator, vertically movable means resting upon the warp threads and connected to the drop member whereby upon tightening of the threads said means will be raised and the drop member will be moved into the path of the vibrator to stop the latter.
- 20 4. In combination with a loom and the stop motion thereof, and means to engage the latter, vertically movable means engaged with the warp threads and operable upwardly upon tightening thereof and connected to the stop motion engaging means for actuating the stop motion.
- 25 5. In combination with a stop motion of a loom, vertically movable means engaged with the warp threads and operable upwardly upon tightening thereof for actuating the stop motion, and means for positively locking the first named means upon operation thereof by the threads.
- 30 6. In combination with the vibrator of a loom and the drop member, a rod adapted to engage on top of the warp threads, vertically movable arms connected to the rod, means connecting the arms to the drop member whereby upon raising of the arms

the drop member will be moved into the path of movement of the vibrator, and means to lock the arms in raised position 45 upon actuation thereof by tightening of the threads.

7. In combination with the vibrator and drop member of a loom, a vertically and upwardly movable device operable by tightening of the threads and connected to the drop member for moving the latter into the path of travel of the vibrator, and means for effecting locking of said device to hold same in up position upon actuation thereof 55 by the threads.

8. In combination with a loom and the stop motion thereof, means resting upon the warp threads and movable upwardly upon tightening of the latter means connected to 60 the first means for contact with the stop motion upon upward movement of the first means, said first means having rack teeth associated therewith, and a pawl engageable with the rack teeth upon upward movement 65 of said means incident to tightening of the threads to lock said means against downward movement.

9. In combination with a loom and the stop motion thereof, an upwardly movable 70 member resting upon the warp threads, a pivoted element connected at one end to said member, and means pivoted to the opposite end of said element and operable thereby to actuate the stop motion. 75

In testimony whereof we have signed our names to this specification in the presence of two subscribing witnesses.
